[57] CLAIM

The ornamental design for a diffuser for a night light or
similar article, as shown and described.

DESCRIPTION

FIG. 1 is a top plan view of a diffuser for a night light
or similar article showing my new design;

FIG. 2 is a front elevational view thereof;

FIG. 3 is a right side elevational view thereof, the left
side being a mirror image;

FIG. 4 is a rear elevational view thereof;

FIG. 5 is a bottom plan view thereof.

FIG. 4

FIG. 5

FIG. 3

FIG. 1

FIG. 2
